(57) CLAIM

I claim the ornamental design for a cup and accessory holder, as shown and described.

DESCRIPTION

FIG. 1 is a front, perspective view of a cup and accessory holder showing the new design;

FIG. 2 is a front, elevation view thereof;

FIG. 3 is a rear, elevation view thereof;

FIG. 4 is a right-side view thereof;

FIG. 5 is a left-side view thereof;

FIG. 6 is a top view thereof;

FIG. 7 is a bottom view thereof;

FIG. 8 is a front, perspective view thereof;

FIG. 9 is a front, elevation view thereof;

FIG. 10 is a rear, elevation view thereof;

FIG. 11 is a right-side view thereof;

FIG. 12 is a left-side view thereof;

FIG. 13 is a top view thereof; and,

FIG. 14 is a bottom view thereof.

The broken lines shown are included for the purpose of illustrating coat hooks and advertisement sleeves which can be optionally affixed to the cup and accessory holder and form no part of the claimed design.
